LENS CLUSTER UNIT FOR PHOTOPRINTING

Richard M. Artz, 3092 Silverton Road NE,
Salem, Oreg. 97308

Filed Feb. 28, 1972, Ser. No. 230,205

Term of patent 7 years

Int. Cl. D16—03

U.S. CL. D61—1 Q

FIG. 1 is a top plan view of a lens cluster unit for photoprinting;

FIG. 2 is a side elevation view of the lens mount, taken in the direction of the arrows 2—2 of FIG. 1;

FIG. 3 is an elevational view taken in the direction of arrows 3—3 of FIG. 1;

FIG. 4 is an elevational view taken in the direction of the arrows 4—4 of FIG. 1;

FIG. 5 is a bottom plan view of FIG. 1;

FIG. 6 is an elevational view taken in the direction of the arrows 6—6 of FIG. 1.

I claim:

The ornamental design for a lens cluster unit for photoprinting, as shown and described.
